US00D733865S

(12) **United States Design Patent**
Ely

(10) **Patent No.:** US D733,865 S
(45) **Date of Patent:** ** Jul. 7, 2015

(54) **EARPLUG SWITCH**

(71) Applicant: **3M INNOVATIVE PROPERTIES COMPANY**, St. Paul, MN (US)

(72) Inventor: **Jacob H. Ely**, Indianapolis, IN (US)

(73) Assignee: **3M Innovative Properties Company**, St. Paul, MN (US)

(**) Term: **14 Years**

(21) Appl. No.: **29/482,288**

(22) Filed: **Feb. 17, 2014**

(51) LOC (10) Cl. **24-04**

(52) U.S. Cl.

USPC **D24/106**

(58) **Field of Classification Search**

USPC D24/106, 173, 174; D8/16, 19; D13/169, 173, 174; D14/205, 206, D14/223; D29/112

CPC A61F 11/008; A61F 11/08; A61F 11/085

(57) **CLAIM**

The ornamental design for an earplug switch, as shown and described.

DESCRIPTION

FIG. 1 is a perspective view showing a new design for an earplug switch;

FIG. 2 is a left side view thereof;

FIG. 3 is a right side view thereof;

FIG. 4 is a rear view thereof;

FIG. 5 is a front view thereof;

FIG. 6 is a top view thereof; and

FIG. 7 is a bottom view thereof;

FIG. 8 is a perspective view of the earplug switch shown on an alternate device;

FIG. 9 is a left side view thereof;

FIG. 10 is a right side view thereof;

FIG. 11 is a rear view thereof;

FIG. 12 is a front view thereof;

FIG. 13 is a top view thereof; and,

FIG. 14 is a bottom view thereof.

The broken line showing of portions of the article is included for the purpose of illustrating internal boundaries with the broken line itself and the area within forming no part of the claimed design, and is not an indication of texture, gloss, etc.

1 Claim, 7 Drawing Sheets

US D733,865 S
